WASH BOILING APPARATUS

Filed Jan. 28, 1927

UNITED STATES PATENT OFFICE.

BERNARD PHILLIPS, OF MIAMI, FLORIDA, ASSIGNOR OF FORTY-NINE PER CENT TO KWART BROTHERS, OF MIAMI, FLORIDA.

WASH-BOILING APPARATUS.

Application filed January 28, 1927. Serial No. 164,355.

This invention relates to the class of laundry, and has more particular reference to an improved form of wash boiling apparatus.

5 The primary object of the present invention is to provide an improved apparatus of the above kind which is simple and durable in construction as well as efficient in use, and which embodies a stove or furnace construction combined with a clothes boiling receptacle.

10 A more specific object of the invention is to provide a wash boiling apparatus of the above kind wherein the stove or furnace construction is extremely simple and cheap to manufacture, and wherein the furnace embodies a grate structure as well as means for facilitating handling and removal of ashes, which are of improved form.

15 Still another object is to provide a furnace construction for wash boiling apparatus of the above kind wherein a removable ash pan is associated with the body of the stove or furnace for being readily positioned beneath the grate to receive the ashes falling therethrough, and which may be readily removed for disposal of the ashes in a convenient manner.

20 Other objects will become apparent as the nature of the invention is better understood, and the same consists in the novel form, combination and arrangement of parts herein-after more fully described, shown in the accompanying drawing and claimed.

25 In the drawing, wherein like reference characters indicate corresponding parts throughout the several views,

30 Figure 1 is a top plan view of the stove or furnace forming part of my improved wash boiling apparatus, with the wash boiling receptacle or vessel removed;

35 Figure 2 is a front elevational view thereof with the wash boiling vessel indicated in place or operative position by dotted lines;

40 Figure 3 is a view partly in side elevation and partly in central vertical section on line 3—3 of Figure 2, with the wash boiling vessel in place; and

45 Figure 4 is an enlarged fragmentary vertical section through the bottom of the stove or furnace body and grate and through the adjacent removable ash pan, taken substantially upon line 4—4 of Figure 1.

50 Referring more in detail to the drawing, the present wash boiling apparatus embodies

a portable furnace structure including a cylindrical body 5 preferably formed of sheet metal and provided with a bottom wall 6 having a rectangular opening therein at the front of the body, the latter being open at 60 its upper end for supporting reception of a conventional or other preferred form of clothes receiving and boiling vessel 7. The vessel 7 is of upwardly flaring form as usual so as to be readily set within the upper end 65 of the body 5 with the larger upper end portion thereof engaging the upper edge of the body 5 so as to be supported by the latter at the required elevation above the bottom 6. The lower portion of the body 5 and its 70 bottom wall 6 is provided with a refractory lining 8 forming a fire pot directly beneath the vessel 7, and the bottom portion 9 of this lining is formed with an opening coincident with the opening in the bottom wall 6 of the 75 body 5 and slightly larger than the latter so that a projecting flange is formed on the bottom wall 6 within the opening of the bottom lining portion 9 as at 10. Removably fitted in the opening of the bottom lining 80 portion 9 is a grate unit 11 preferably of integral cast construction as shown. This grate 11 is disposed with its margin resting upon the flange 10 of the bottom wall 6 so that said grate is properly supported in place 85 although capable of being readily removed for renewal or repair by lifting the same upwardly from its operative position. Provided in the body 5 and lining 8 at the front of the furnace directly above the grate 11 90 are aligned openings adapted to be closed by a hinged door 12, and it is thus apparent that upon opening the door additional fuel may be supplied to the fire pot from time to time as found necessary, while a poker 95 may also be introduced if desired through the registered openings for agitating the fuel and causing the ashes to fall through the grate. The body 5 is supported at an elevation with its bottom wall 6 a slight distance above the supporting surface, by means of a plurality of supporting legs 13, each of which preferably consists of a strip of rigid or stiff metal fastened at its upper end as by riveting or the like at 14 to the lower end of the body 5, the lower end of the strip being provided with a lateral or out-turned lower end forming a foot 15 for flat contact with the supporting surface. As many of these legs may be provided as 110

found most desirable, but three are believed sufficient, two at the front, and one at the rear, the two front legs being provided at opposite sides of the door 12.

5 Provided on the underside of the bottom wall 6 are a pair of spaced angle strips 16 which may be suitably rigidly fastened in place so as to extend from a point slightly rearwardly of the rear end of the grate 11 to the forward or front side of the body 5 in spaced parallel relation. These angle strips 16 are so related as to have lower inwardly facing flanges, thus providing a pair of opposed guideways in which are slidably engaged the outwardly directed flanges 17 provided upon the upper longitudinal or side edges of an ash pan 18. This ash pan 18 is of a size to receive ashes falling through any part of the grate 11 when in rearwardly slid operative position as shown in Figure 3, and provided upon the front end of said ash pan is a sheet metal handle 19 adapted to be conveniently grasped for facilitating the removal and replacement 25 of the same. Secured to the upper edge of the front wall of the ash pan 18 is an arcuate tray 20 adapted to project at the front of the furnace body when the ash pan is operatively positioned. This tray is thus disposed to catch any ashes or live coals which may fall outwardly through the opening closed by door 12 should the same be opened, and the handle 19 is preferably of angular form having one end fastened to the underside of tray 20 and its other end fastened to the outer end of the pan 18 as shown clearly in Figure 3.

An opening is provided in the back of the body 5 near the top of the latter or above the lining 8, and said body 5 is formed with an integral projecting flange 21 about this opening adapted to receive one end of an elbow 22 provided upon the lower end of a smoke pipe 23. This smoke pipe extends upwardly from the elbow 22 to the required distance where it is provided at its upper end with a suitable cowl generally indicated at 24, which enables practical use of the device in an unsheltered place or outside of 45 a dwelling, such as in the back yard of a residence or the like.

In use, fuel is suitably introduced through the opening closed by door 12 and ignited to provide a fire within the fire box and 55 partially upon the grate 11. The vessel 7 is then placed in position within the upper end of the furnace body 5 as shown in Figure 3, whereupon said vessel 7 is partly filled with water that is brought to the boiling point. Upon then placing the clothes

within the vessel 7 they may readily be boiled as and for a purpose which is well known in the art. When the clothes have been sufficiently boiled they may be removed by bodily lifting the vessel 7 from the furnace body, in a convenient manner. By 65 opening the door 12, the required attention may be given to the fire from time to time, and any ashes falling or caused to fall through the grate 11 will be caught in the ash pan 18. Such fuel or ashes as may fall at the front of the body under ordinary circumstances will be caught by the tray 20, and when the ash pan 18 becomes filled with 70 ashes, it may be readily removed and the ashes dumped therefrom. This removal of the pan is effected by simply grasping the handle 19 and sliding the pan 18 forwardly until its flanges 17 ride entirely out of the guideways formed by the angle strips 16. 80 When the ashes have been dumped, the empty pan may again be replaced by engaging the flanges 17 in the guideways and sliding the pan to its rearmost position. The rearward movement of the pan 18 to 85 operative position may be limited by so disposing the tray 20 as to have the latter abut the body 5 of the furnace.

From the foregoing description, it will be seen that I have provided a wash boiling apparatus which is extremely simple and durable in construction and efficient in use, and which may be used to advantage where gas and electricity are not available or where the latter fuels are not capable of practical 95 employment in the open.

Minor changes may be made without departing from the spirit and scope of the invention as claimed.

What I claim as new is:—

In a wash boiling apparatus, a portable furnace including an upright body provided with a front opening for the supply of fuel, said body further having a bottom wall with the forward edge thereof terminating at the 100 lower edge of the upright wall and having an opening in the forward portion thereof, a grate supported in said opening, an ash pan slidably positioned beneath the bottom wall of the body and grate, an arcuate tray 105 rigid with the upper edge of the outer side wall of the ash pan to project forwardly of the body below the fuel opening, the inner edge of the tray terminating flush with the front wall of the body, and a lifting handle 110 attached to the tray and having a bracing part engaging the ash pan.

In testimony whereof I affix my signature.

BERNARD PHILLIPS.
